AUTOMATIC FIRE ALARM OR SIMILAR ARTICLE

Werner Buhrer, Uetikon am See, Switzerland, assignor to
Cerberus AG, Mannedorf, Switzerland

Filed Nov. 12, 1969, Ser. No. 20,045

Claims priority, application Switzerland May 12, 1969

Term of patent 14 years

Int. Cl. D29—01

U.S. Cl. D72—1

FIG. 1

FIG. 2

FIG. 3

FIG. 1 is a perspective view of an automatic fire alarm or similar article showing my new design.

FIG. 2 is a side elevational view thereof, the opposite side being identical to the side shown.

FIG. 3 is a bottom plan view thereof.

The top surface of the fire alarm, not shown, is substantially planar and circular.

I claim:

The ornamental design for an automatic fire alarm or similar article, as shown and described.
